METAL-CUTTING SYSTEM

Paul Georges Chevigny, New York, N. Y., assignor to Federal Telephone and Radio Corporation, New York, N. Y., a corporation of Delaware

Application October 16, 1944, Serial No. 558,947

17 Claims. (Cl. 164—60)

1
This invention relates to metal working and more particularly to a method and means for partially splitting a layer or lamina from the face of a metallic member.

In the manufacture of vacuum tubes whose envelope includes a metallic section and a glass section, the glass section is hermetically sealed to the metallic section to produce a unitary structure. This metallic section must be so constructed that it will be impervious to gas and liquid and also resist mechanical strains, and therefore, it is important that the construction of the metallic section shall be without imperfections.

When external disc type cutters are used to split a metallic member of circular configuration to produce a lamina thereon, relatively high amounts of friction develop between the cutter and the metallic member thereby causing certain strains upon the metal of said metallic member rendering it useless as a metallic section in vacuum tubes, or for many other purposes.

In splitting a lamina from a metallic member, the metallic member is generally rotated in one direction, and when the cutter is moved into cutting engagement with the member it is rotated thereby in the opposite direction. As the peripheral cutting edge of the cutter can only make a point contact with the metallic member in the splitting operation there is a tendency to tear the metallic member thereby causing not only friction therebetween, but also a certain amount of strain upon the grains of the metallic member.

As most of these types of cutters are provided with beveled cutting edges to raise the lamina from the metallic member, a relatively high degree of tension upon the grains of metal on the underside of the lamina is imposed upon the already strained metal. As this lamina is to be further treated by rolling to produce a feathered edge for sealing the metallic member to a glass member, the strains and microscopic imperfections caused by the cutter will result in vertical cracks or other imperfections.

It is therefore, one of the objects of this invention to provide an improved method of and means for splitting a metallic member that overcomes the disadvantages mentioned above.

Another object is to provide a method and means for splitting disc members with considerably less friction between the cutter and the metallic member than heretofore experienced in existing cutting devices.

Still another object is to provide improved cutting means.

Further objects will become apparent upon ref-

2
erence to the following detailed description taken in connection with the accompanying drawings, in which:

Fig. 1 is a plan view of one embodiment employed in carrying out the method of this invention.

Fig. 2 is a vertical sectional view taken along lines 2, 2 of Fig. 1.

Fig. 3 is a diagrammatic plan view of a modified embodiment of the apparatus employed in carrying out the method of this invention,

Fig. 4 is a diagrammatic plan view of a still further embodiment of the apparatus employed in carrying out the method of this invention; and

Figs. 5, 6, 7, 8 and 9 are vertical sectional views of a number of different cutters which may be employed in carrying out the method of this invention.

The apparatus shown in Fig. 1 to carry out the method of splitting a lamina from a metallic disc, such as copper, is provided with a base 1, having a vertical boss 2, and spindle 3 adapted to receive a freely rotatable disc 4, from which the lamina is to be split. The base 1 is also provided with a smooth upper face 5 upon which is slidably mounted a cutter supporting member 6. This supporting member 6 is provided with an annular ball bearing race 7, which rotatably supports an arcuate-cutter 8 in its rotation about its axis 9.

These arcuate cutters may be formed as annular bodies having at least the major portion of their inner peripheries shaped to provide inwardly disposed cutting edges.

Although the arcuate cutter shown in Figs. 1, 2 and 7 is preferably formed as an annular body having the inner periphery shaped to provide a cutting edge, which may be formed in the shape of a spiral as shown in Fig. 4. The annular body 40 may also have the inner peripheries shaped similarly as shown in Figs. 5, 6, 8 and 9 to provide single cutting edges with either one of two deviating surfaces, or as shown in Figs. 7 and 9, to provide a pair of parallel cutting edges each having a deviating surface. The deviating surfaces may have in cross section the appearance of either beveled surfaces as shown in Figs. 5, 6 and 7, or dish-shaped surfaces 11a as shown in Figs. 8 and 9. The arcuate cutters 8 in Figs. 1, 2 and 7 is preferably provided with a pair of spaced-apart parallel cutting edges 10, the upper cutting edge having a single upwardly deviating surface or bevel 11 while the lower cutting edge is provided with a single downwardly deviating surface or bevel 12.

While the cutter 8 is shown constructed in one piece, it is to be understood, that the cutter could be made of two or three pieces and assembled together to form a unitary structure.

A pulley 13 fastened to the underside of the cutter 8 is adapted to be driven by a motor 14 by means of a pulley 15 and a continuous belt 16. As the motor 14 is fastened to one end of the cutter supporting member 6, the belt will always remain taut throughout the cutting operation. The base 1 is also provided on two sides with vertical guide walls 17 and 18 between which the cutter supporting member 6 is freely guided in the splitting operation. On the base 1 opposite the motor there is provided an abutment 19 into which is threaded a screw 20, one end of which is rotatably fastened to the cutter supporting member 6, and the other end of which is provided with a crank 21. Rotation of this crank will move the cutter supporting member 6 together with its associated parts into or out of engagement with the disc 4.

After the disc 4 has been placed for rotation upon the spindle 3, the motor 14 may be started to drive the annular cutter in the direction shown by the arrow. By the proper turning of the crank 21 the supporting member 6 and its associated parts are moved toward the disc 4 until the cutting edge of the cutter engages and rotates the disc in the same general direction. Further rotation of the crank 21 forces the cutting edge of the cutter 8 into the peripheral face of the disc 4. As the cutter enters into the disc in a radial direction the deviating or beveled surfaces 11 and 12 of the cutter will gradually lift the layer or lamina L from the disc and into the configuration of a coaxially aligned, hollow truncated cone.

From the foregoing operation of the apparatus in splitting the lamina it will be seen that the friction between the cutter and disc will be greatly reduced by rotating both the disc and cutter in the same general direction. Further, the inwardly curved shape of the cutting edge contacting the disc material makes more gradual the cutting force exerted by the cutter upon the disc material. Consequently, the strain upon the grains of the disc material will be greatly reduced.

When the cutter and disc are brought into engagement with each other, one will drive the other consequently reducing the friction therebetween and also reducing the tension upon the grains of the metallic member.

It may also be found desirable to move the disc along a spiral path about the axis of the cutter and thereby gradually move it into the driven cutter. The cutter although free to rotate would have its axis of rotation fixed as shown in Fig. 3 of the drawings.

While I have described above the principles of this invention in connection with specific apparatus, it is to be clearly understood that this description is made only by way of example and not as a limitation on the scope of the invention as set forth in the objects and accompanying claims.

I claim:

1. A method of laterally splitting a metallic disc element inwardly from its circumferential face comprising the steps of applying an inwardly curved cutting element to said face, rotating one of said elements, producing relative transverse movement between the cutting edge of said cutting element and the circumferential

face of said disc element during rotation of at least one of said elements, and continuing said rotary movement of said one of the elements until said disc element is split a desired depth.

5. 2. A method of laterally splitting a metallic disc member inwardly from its circumferential face comprising the steps of applying an inwardly curved cutting element to said face, rotating one of said elements, moving one of said elements toward the other for engagement therewith, thereby causing said disc element and said cutting element to rotate in the same rotary direction, and continuing the movement of one of said elements toward the other to split said disc.

10 3. A method of laterally splitting a metallic disc member inwardly from its circumferential face comprising the steps of applying an inwardly curved cutting element to said face, rotating one of said elements, moving one of said elements toward the other for engagement therewith, thereby causing said disc element and said cutting element to rotate in the same rotary direction, and continuing said movement of one of said elements toward the other to split said disc, and forcing at least one part of the split disc gradually laterally with respect to the plane of rotation of said disc as the depth of the split increases.

15 4. Means for laterally splitting a metallic disc element inwardly from its circumferential face comprising an inwardly curved cutting element provided with a cutting edge at its inner periphery, means for rotatably supporting said cutting element, means for rotatably supporting a metallic disc element within the arc of rotation of said cutting element, means for rotating at least one of said elements, means producing relative transverse movement between the cutting edge 20 of said cutting element and the circumferential face of said disc, whereupon the rotary movement of said one of said elements drives the other of said elements and said cutting edge is forced laterally into said disc.

25 5. Means for laterally splitting a metallic disc element inwardly from its circumferential face comprising an inwardly curved cutting element provided with a cutting edge at its inner periphery, means for rotatably supporting said cutting element, means for rotatably supporting a metallic disc element within the arc of rotation of said cutting element, means for rotating at least one of said elements, means for moving at least one of said elements toward the other of said elements whereby the cutting edge of said cutting element will contact the circumferential face of said disc element, whereupon the rotary movement of said one of said elements drives the other of said elements and said cutting edge is forced laterally into said disc.

30 6. Means for laterally splitting a metallic disc element inwardly from its circumferential face and forcing at least one portion of the split disc gradually laterally with respect to the plane of rotation of said disc comprising an inwardly curved cutting element having two intersecting surfaces forming a cutting edge at its inner periphery one of said surfaces being parallel to said plane of rotation and the other deviating from 35 said plane of rotation, means for rotatably supporting said cutting element, means for rotatably supporting a metallic disc element within the arc of rotation of said cutting element, means for rotating at least one of said elements, means for producing relative transverse movement be- 40

45 70 75

tween the cutting edge of said cutting element and the circumferential face of said disc element, whereupon the rotary movement of said one of said elements drives the other of said elements and said cutting edge is forced into said disc thereby forcing at least one portion of the disc gradually laterally with respect to the plane of rotation of said disc.

7. A metallic disc-splitting means according to claim 6 wherein the cutting element includes two additional intersecting surfaces forming a pair of spaced-apart cutting edges at its inner periphery, one of said additional surfaces being substantially parallel to and spaced apart from said one of said surfaces and the other of said additional surfaces deviating from said plane of rotation.

8. A metallic disc-splitting means according to claim 6 wherein the cutting element includes two additional intersecting surfaces forming a pair of spaced-apart cutting edges at its inner periphery, one of said additional surfaces being substantially parallel to and spaced apart from said one of said surfaces and the other of said additional surfaces deviating from said plane of rotation and in a direction opposite said other deviating surface.

9. Means for laterally splitting a metallic disc element inwardly from its circumferential face and forcing at least one portion of the split disc gradually laterally with respect to the plane of rotation of said disc comprising an inwardly-curved cutting element having two intersecting surfaces forming a cutting edge at its inner periphery, one of said surfaces being parallel to said plane of rotation and the other deviating dish-shaped in cross section from said plane of rotation, means for rotatably supporting said cutting element, means for rotatably supporting a metallic disc element within the arc of rotation of said cutting element, means for rotating at least one of said elements, means for producing relative transverse movement between the cutting edge of said cutting element and the circumferential face of said disc element, whereupon the rotary movement of said one of said elements drives the other of said elements and said cutting edge is forced into said disc, thereby forcing at least one portion of the disc gradually laterally with respect to the plane of rotation of said disc.

10. A metallic disc-splitting means according to claim 9 wherein the cutting element includes two additional intersecting surfaces forming a pair of spaced-apart cutting edges at its inner periphery, one of said additional surfaces being substantially parallel to and spaced apart from said one of said surfaces and the other of said additional surfaces deviating dish-shaped in cross section from said plane of rotation.

11. A metallic disc-splitting means according to claim 9 wherein the cutting element includes two additional intersecting surfaces forming a pair of spaced-apart cutting edges at its inner

periphery, one of said additional surfaces being substantially parallel to and spaced apart from said one of said surfaces and the other of said additional surfaces deviating dish-shaped in cross section from said plane of rotation and in a direction opposite said other deviating dish-shaped surface.

12. Means for laterally splitting a metallic disc element inwardly from its circumferential face and forcing at least one portion of the split disc gradually laterally with respect to the plane of rotation of said disc comprising an inwardly-curved cutting element having two intersecting surfaces forming a cutting edge at its inner periphery, one of said surfaces deviating from said plane of rotation and the other of said surfaces deviating from said one of said surfaces and said plane of rotation, means for rotatably supporting a metallic disc element within the arc of rotation of said cutting element, means for rotating at least one of said elements, means for producing relative transverse movement between the cutting edge of said cutting element and the circumferential face of said disc element, whereupon the rotary movement of said one of said elements drives the other of said elements and said cutting edge is forced into said disc thereby forcing at least one portion of the disc gradually laterally with respect to the plane of rotation of said disc.

13. A metallic disc-splitting means according to claim 12 wherein the intersecting surfaces deviate in directions opposite one another.

14. A cutting element comprising a substantially annular body having the major portion of the inner periphery thereof formed by two intersecting surfaces to provide inwardly disposed cutting edge, each of said intersecting surfaces being dish-shaped in cross section.

15. A cutting element comprising a substantially annular body adapted for rotation about the axis thereof, said body having the major portion of the inner periphery thereof formed by four surfaces, two of which are substantially parallel to the plane of rotation of said body and the other two of which deviate from said plane of rotation.

16. A cutting element according to claim 15 wherein the two deviating surfaces of said body are dish-shaped in cross section.

17. A cutting element according to claim 15 wherein the two deviating surfaces are disposed in opposite directions.
